(57) **CLAIM**

I claim the ornamental design for a wafer support ring, as shown and described.

DESCRIPTION

FIG. 1 is a top plan view of a wafer support ring according to an embodiment of the invention.

FIG. 2 is a top perspective view of the wafer support ring depicted in FIG. 1.

FIG. 3 is a cross-sectional view of the wafer support ring taken at line 3-3 of FIG. 1.

FIG. 4 is a cross-sectional view of the wafer support ring taken at line 4-4 of FIG. 1.

FIG. 5 is a cross-sectional view of the wafer support ring taken at line 5-5 of FIG. 1.

FIG. 6 is a left elevational view of the wafer support ring.

FIG. 7 is a front plan view of the wafer support ring.

FIG. 8 is a bottom perspective view of the wafer support ring; and,

FIG. 9 is a bottom plan view of the wafer support ring.
